UNITED STATES PATENT OFFICE

CARL WINNER, OF HAMTRAMCK, MICHIGAN

POWER GANG FILING DEVICE

Application filed November 30, 1928. Serial No. 322,781.

The object of my invention is to produce a gang filing device adapted for filing several parallel openings at the same time and operated by power means.

Another object is to produce a special gang filing device which is particularly adapted for removing the rough edges within the wiring slots of electric starter and generator armature cores, where these slots are parallel and arranged in a circle about the outer circumference of the armature.

A further object is to produce a gang filing device actuated by a slidable filing head and power crank mechanism, that is constructed with adjustable parallel files, all capable of radial adjustment against spring supports for forming contact with the work.

Another object is to produce a power gang filing device so designed that all of the files will operate alternately sidewise and edgewise with each movement of the operating crank.

These several objects are attained in the preferred form by the construction and arrangement of parts more fully hereinafter set forth.

Similar parts on all drawings are marked by similar numerals.

Fig. 1 is front view of the gang filing device showing the exterior arrangement of the gang filing head and file operating mechanism.

Fig. 2 is a side view of the device showing the relative position and general arrangement of the file operating mechanism.

Fig. 3 is a top view of the device showing the general arrangement of the various gang files and clamping cams.

Fig. 4 is a sectional view taken on the line 4—4 of Fig. 2, showing the multiple file holders with files and the relative position of the work clamps.

Fig. 5 is a vertical section taken on the line 5—5 of Fig. 2 showing the construction of the interior operating mechanism.

Fig. 6 is also a vertical section taken on the line 6—6 of Fig. 1 showing the relative positions of the operating mechanism.

Fig. 7 is sectional view through the base taken on the line 7—7 of Fig. 2 showing the crank operating mechanism and power unit.

Fig. 8 is an enlarged detail of one file holder and file as taken on the line 8—8 of Fig. 3 showing the means for adjusting the file edgewise.

Fig. 9 is a top view of the file holder shown in Fig. 8 showing the spring clip for retaining the file within the holder.

Fig. 10 is a sectional view taken on the line 10—10 of Fig. 6 showing the operating cam for producing sidewise movement of the filing head.

Fig. 11 is a front view of the same cam mechanism where the cam block is made with a double slot instead of a single straight slot as shown in Fig. 10, and may be substituted therefor.

I will now describe more fully the detailed construction of my device, referring to the drawings and the marks thereon.

In general my device comprises a base casting having a circular gang filing head slidably mounted on a vertical shaft, all oscillated vertically by connected crank mechanism installed within the base casting, and driven by an electric motor. The gang filing head is constructed with a series of vertically positioned files, adjustably retained therein by fixedly attached file holders, all of which oscillates with the gang filing head. Suitable holding mechanism is mounted above the series of gang files for retaining the work in a fixed rigid position for engaging the files during their oscillatory movement.

The base casting —1— is preferably made of a box shaped structure, with either open side walls, or closed as indicated in the drawings in Figs. 1 and 2, and is formed with a horizontal support —2— near the base of the casting. Fixedly mounted on the supports —2— are two crank bearings —3—, positioned parallel with each other, and carry a crank —4— rotatably mounted therein. Fixedly attached to the crank —4— is a driving pulley —5— which may rotate therewith and is securely keyed thereon. Rotatably mounted on the crank —4— is an idler pulley —6— which turns freely on the shaft and is retained thereon by the end collar —7— fixedly attached to the outer end of the shaft. A motor —8— is mounted on the horizontal

support —2—, the motor being provided with a driving pulley —9— positioned in alignment with the shaft pulleys —5— and —6—, and is connected thereto by the drive belt —10— for imparting operating power to the crank —4—. The motor —8— is provided with connections to an electric circuit through the terminals —11— and —12— in the usual manner. Slidably mounted through the walls of the crank bearings —3— is the belt shift bar —13—, provided with belt pins —14— positioned therein to engage the belt —10— in a manner for shifting the belt from the idler pulley —6— to the drive pulley —5—, or back in the reverse order, for starting or stopping the crank rotations. An operating shaft —15— is rotatably mounted beneath the supports —2— and carries fixedly attached thereto a foot lever —16— for causing partial shaft rotations in either direction. On the inner end of the shaft —15— is mounted a slotted arm —17—, arranged to engage an operating pin —18— which projects from the side of the belt shift bar —13—, causing a sliding movement of the bar —13— and a shifting of the belt —10— from one pulley to the other as the shaft —15— is turned. Mounted within the top wall of the base casting —1— is a filing head shaft —19—, positioned therein vertically and in true alignment with the crank shaft —4—, and supported by the bearings —20— and —21—, but free to slide therein. The lower end of the filing head shaft —19— is formed with a ball bearing end —22—, and carries movably mounted thereon a connecting rod —23—. The connecting rod —23— is rotatably attached to the crank —4— at the lower end by the bearing —24— and rotates therewith, causing a vertical oscillating movement of the filing head shaft —19— when said crank is rotated by the motor —8—. Fixedly attached to the top end of the shaft —19— is a circular head collar —25—, the top face of which is positioned at right angles to the supporting shaft. Fixedly attached to the top face of head collar —25— is a gang file head —26—, the same being securely clamped thereto by the bolts —27—. The gang file head —26— is formed with a series of recesses —28— and —29—, positioned in pairs, radially and in concentric circles about the axis of the filing head shaft —19—. The recesses —28— carry mounted therein vertically positioned file holders —30—, all securely attached by the set screws —31—. The recesses —29— receive the bottom end of the files —32— which slides therein. The file holders —30— are formed with a spring recess —33— at the bottom end thereof and carries a compression coil spring —34— therein, positioned to engage the adjacent face of the files —32— and exert an outward pressure thereon, and causing said file to move along the slotted recess —29— toward the center of the file head —26—. The top ends of the file holders —30— are all formed with a recess —35— for receiving the file lip —36— therein. The file lip —36— being formed thin and as a part of the file —32—. A coil compression spring —37— is placed within the recess —38— within each of the file holders, and so engages the file lips —36—, also causing an inward radial pressure thereon. A spring clip —39— is attached to the top ends of all of file holders —30—, and engages a pin —40— fixedly mounted within the top edge of the file lips —36—, said pins —40— slidably mounted within the slots —41— of the spring clips. Fixedly mounted on the top face of the base casting —1— is an L-shaped housing casting —42—, securely attached to the base by the bolts —43—. Through the top L-shaped end of the housing casting —42— is mounted a vertical work shaft —44—, slidably mounted within the bearings —45— and —46—, said work shaft —44— being positioned in true alignment with the axis of the filing head shaft —19— and concentric therewith. The work shaft is provided with a lift collar —47— fixedly attached thereto by the set screw —48—, and supports the end of a balance cable wire —49—. On the top of the housing casting —42— is mounted a cable roller —50—, also within the body of the hollow housing casting is mounted a cable roller —51—, both rollers receiving the balance cable wire —49— therein, and may rotate under movement of said cable wire. The cable wire carries a balance weight —52— attached thereto, and of a weight sufficient to approximately balance the weight of the work shaft —44— and attached mechanism which it carries at the lower end thereof. The inner face of the work shaft —44— is formed with gear teeth —53—, which engage and mesh with an operating gear —54—. The operating gear —54— is mounted on the shaft —55— which is rotatably mounted in the bearing —56— of the housing casting. An operating wheel —57— is attached to the shaft —55—, providing means for raising and lowering the work shaft —44— and attached mechanism. Fixedly attached to the lower end of the work shaft —44— is a work supporting disc —58—, and securely held thereon by the nut —59—, the shaft end projecting through the nut —59— sufficiently for engaging and centering the work thereon. The disc —58— is provided with a heavy receding coil spring —60—, to allow slight adjustment of the disc should too great a pressure be applied thereon. Slidably mounted on the work shaft —44—, just above and adjacent to the supporting disc —58— is a clamp head —61—. Pivotedly mounted in the lower face of the clamp head —61— are a series of hooked clamp fingers —62—.

which extend over and project below the work supporting disc —58—, said hooked fingers being formed and positioned to engage a circular piece of work —63— and securely clamp same therein against the work supporting disc —58—. The clamp fingers —62— are so formed with beveled inner surfaces that they will slide open when pressed downward on the disc —58—, but will close when lifted up under action of the closing spring —64—. Fixedly attached to the work shaft —44— directly above and adjacent to the clamp head —61— is a rigid cam block —65—, the same being attached thereto by the pin —66—. Slidably mounted through vertical bearings —67— of said cam block, are two finger operating bars —68—, and which have their lower ends fixedly attached to the clamp head —61—. The upper ends of the operating bars —68— being pivoted to operating locking cams —69— by the pins —70—. The cams —69— are formed with an operating handle —71— providing means for turning them for raising or lowering the connected clamp head —61— and attached clamp fingers —62—. A heavy coil spring —72— is placed between the cam block —65— and clamp head —61— for forcing the clamp head downward on the shaft when the locking cams —69— are released, and thus releasing the inclosed work —63—. When a circular piece of work —63— which is formed with a series of parallel circumferential grooves —73—, is securely clamped against the work holding disc —58— by the hooked clamp fingers —62— under pressure from the locking cams —69—, the said work —63— may be lowered over the series of gang files —32—, the files —32— being passed through the circumferential grooves —73— of the work, and when the gang file head is oscillated by the connected crank —4—, the work grooves —73— are subjected to the cutting action of the files —32—, which are held firmly against the work by the file springs —34— and —37—. To produce a spiral movement of the filing shaft —19— for causing side cutting of the files —32—, a torsion collar —74— is fixedly mounted on the shaft —19— below the upper shaft bearing —20—, and is securely attached thereto by the set screw —75—. The torsion collar —74— carries mounted thereon a roller —76— projecting from the back side thereof and free to rotate on its connecting pivot. The roller —76— engages an angularly shaped slot —77— formed within a movable cam block —78—, and which causes a spiral movement of the shaft —19— as it moves backward and forward therein. The cam block —78— is provided with side springs —79— to allow for slight adjustment of said cam and for causing side pressure on the files.

65 While I have shown the device with a sin-

gle straight cam slot —77—, illustrated in Fig. 10, said slot may be modified by a double slot as shown in Fig. 11, or by any number of cam variations desired.

Having fully described my power gang filing device, what I claim as my invention and desire to secure by Letters Patent is;

1. A gang filing device adapted for filing a series of parallel work slots simultaneously, comprising a rigid housing frame having a gang file head slidably mounted therein, power means attached to said gang file head by suitable mechanism for producing an oscillatory movement thereof, a series of parallel files mounted within said gang file head, and means mounted on said housing frame for rigidly supporting work pieces within said file head.

2. A gang filing device adapted for filing a series of parallel work slots in machined parts simultaneously, comprising a rigid housing frame, a gang file head slidably mounted within said housing, crank means mounted within said housing frame and connected to said gang file head in a manner to produce oscillatory movement thereof as the crank is rotated, power means mounted within said housing frame and connected to said crank for causing rotations thereof, a series of files mounted within said gang file head all positioned parallel to each other and to the axis of travel of the said gang file head, a work supporting clutch movably mounted on said housing frame for rigidly holding machined parts to be filed within said series of files.

3. A gang filing device adapted for filing a series of parallel work recesses in machined parts simultaneously, comprising a rigid housing frame, a gang filing head slidably mounted therein on a vertically positioned shaft, crank means rotatably mounted in the base of said housing frame and connected to said gang head shaft by an oscillating connecting pitman, power means applied to said crank for causing rotation thereof, a series of parallel files mounted within suitable supporting frames on said gang filing head, all positioned parallel to each other and the axis of movement of said gang filing head, a work supporting clutch mounted within said housing frame positioned therein in true alignment with the axis of movement of the said file head, and means mounted thereon for lowering said work supporting clutch within the series of parallel files.

4. A gang filing device adapted for filing a series of parallel work recesses within the edges of machined parts simultaneously, comprising a rigid housing frame, a gang filing head mounted therein on a vertical slide shaft, a crank rotatably mounted within the base of said housing frame and connected to said vertical shaft by a connecting pitman and capable of imparting a ver-

tical oscillatory movement thereto as the crank is oscillated, power means mounted within said housing frame and connected to said crank for causing rotation thereof, a series of parallel files mounted within spring file holders and attached to said gang file head, all positioned parallel with the axis of the gang file head shaft, a work shaft slidably mounted within said housing frame, positioned along the axis of the gang file head shaft, means attached thereto for raising and lowering same, a work supporting clutch mounted on the lower end of said work shaft capable of rigidly supporting machined parts and lower same inside the series of parallel files.

5. A gang filing device adapted for filing a series of parallel work recesses in machined parts simultaneously, comprising a rigid 10 housing frame, a movable gang file head slidably mounted within said housing on a vertically positioned sliding shaft, a crank rotatably mounted within the base of said housing and connected to the lower end of the said vertical shaft by a connecting pitman, power means mounted within the housing base and connected to said crank in a manner to cause rotation thereof, a slideable member mounted in the top of said housing frame above said gang file head and in true alignment with the gang head shaft, means mounted on said housing frame for raising or lowering said sliding member, a work supporting clutch mounted on the lower end of said sliding member, said clutch positioned concentric with the gang file head, a series of files mounted within said gang file head by suitable spring file holders and all positioned parallel to each other and the axis of 20 movement of said gang file head, and a spiral cam mounted within said housing frame adjacent to and parallel with the gang file head shaft, and means mounted on said gang file head shaft and engaging said spiral cam for causing a spiral movement to the gang file head and attached files with each crank movement.

In witness whereof I sign these specifications.
